UNITED STATES PATENT OFFICE.

JOSEPH RIDDELL AND JOHN J. MADDEN, OF SHARON, PENNSYLVANIA; SAID MADDEN
ASSIGNOR OF ONE-HALF HIS RIGHT TO SAID RIDDELL.

SERVICE-BOX FOR CONDUITS.

No. 914,186.

Specification of Letters Patent.

Patented March 3, 1909.

Application filed March 5, 1908. Serial No. 418,296.

To all whom it may concern:

Be it known that we, JOSEPH RIDDELL and JOHN J. MADDEN, citizens of the United States, residing at Sharon, Pennsylvania, have invented certain new and useful Improvements in Service-Boxes for Conduits, of which the following is a specification.

Our invention relates to service cock boxes, as employed in connection with gas and water distribution or the like, and is designed chiefly to give the most convenient access to an underground stop cock. Also to protect the same and avoid danger of displacement of the parts by frost or temperature changes. In boxes of this type, heretofore used, it has been difficult for the operator, as a rule, to locate the valve nut with a long key, but in our device this difficulty is reduced to a minimum, as a central position of the stop cock, in relation to the exposed box is assured.

The invention consists in the novel arrangement and combination of parts herein-after described and particularly pointed out in the claim:

In the accompanying drawings; Figure 1 is a perspective view of the device partly broken away, and Fig. 2 is a similar view of the under side of the cap.

The box, as shown, is composed of a metal tube or the like having telescoping members 1 and 2, which permit of any desired vertical adjustment when installing the device. At its lower end this tube or pipe 2 carries a casting 3 of suitable material, secured by a set screw. This casting fits snugly over the main and around the stop cock, thus centering the same in proper position. The casting 3, as shown, is provided with ribs or projections extending from its outer periphery at intervals and these projections have parallel vertical faces which come in contact with the corresponding faces on the ends of the valve casing and tend to hold the valve box or casting rigidly in relation to the casting and thus prevent any displacement of the stop-cock and keep it at all times centrally of the casting. This arrangement also permits the assembling of the parts without change in the relative position of the stop-cock and the casting, as the service pipes may be screwed into the valve box or casting without disarranging the parts by reason of the fact that

the outer faces of the ends of the casing engage the parallel faces of the ribs of the casting.

55

The larger telescoping member 1 is provided at its upper or surface end with suitable projections 4, designed to engage a locking latch or plate 5, carried by the cap or cover 6. The latch 5 is rigidly secured to the cover 6 by fitting into a recess 6^x thereof on the inner or under side and held fast by a screw 7. When necessary, the cover 6 may be easily removed, with a suitable key, by giving a quarter turn thereto in the proper direction. The member 1 is also provided with brackets 8 to insure against any possible dislodgment of the same, these brackets or extensions being embedded in the ground.

From the foregoing description it will be clearly understood that the device is simple in construction, therefore comparatively inexpensive to make, and by its use the surface box is connected with the casting or base within which the stop cock is centrally held so that the surface box is maintained in central relation to the stop cock and by introducing a long key centrally of the surface box and the extended tube connecting the same with the casting, the stop cock may be readily located. All the parts are rigidly secured together and are maintained as one body, and temperature changes and frost will not affect their relative positions.

We do not limit ourselves to the telescopic construction as it may be sometimes more convenient to make the members 1 and 3 in one piece.

We claim as our invention:—

In combination, a stop cock or valve, a 90 casing for the same having angular ends, a casting having its open ends fitted to the angular ends of the valve casing, and external ribs on the casting forming parallel walls to receive the corresponding ends of the valve 95 casing, substantially as described.

In testimony whereof, we affix our signatures in presence of two witnesses.

JOSEPH RIDDELL.
JOHN J. MADDEN.
